UNITED STATES PATENT OFFICE.

CORA H. EVERHARD, OF CANTON, CHIO.

DESIGN FOR A SKIRT-GAGE.

43,527.

Specification for Design.

Patented Feb. 11, 1913.

Application filed July 27, 1912. Serial No. 711,925. Term of patent 7 years.

To all whom it may concern:

Be it known that I, CORA H. EVERHARD, a citizen of the United States, residing at Canton, in the county of Stark and State of Ohio, have invented a new, original, and ornamental Design for a Skirt-Gage, of which the following is a specification, reference being had to the accompanying drawing, forming part thereof.

In said drawing the figure is a perspective view of a skirt gage showing my new design.
I claim:

The ornamental design for a skirt gage, as shown.

CORA H. EVERHARD.

Witnesses:

F. W. BOND,
SYLVIA BORON.
